Specification of Letters Patent. Patented Aug. 25, 1914.

Application filed March 8, 1913. Serial No. 753,068.

To all whom it may concern:

Be it known that I, WILLIAM KLOCKE, a citizen of the United States, residing in Brooklyn, county of Kings, State of New York, have invented certain new and useful Improvements in Presses, of which the following is a specification.

This invention relates to power presses, and more especially to presses designed for heavy work. It aims to provide improvements therein.

The present invention has been based upon experience with presses in which pressures of 1500 tons and over are delivered by the plunger. Practical limitations in the sizes of castings and material are almost reached in presses of the above-mentioned capacity. The demand is for still larger presses. Furthermore, owing to the enormous strains developed in presses of large capacity the amount of deflection or distortion of the parts, owing to the side thrust transmitted from the crank shaft to the plunger through the connecting rod, when the cranks are off center, is so great as to introduce very serious problems in the designing of such presses.

By the present invention means are provided for overcoming the foregoing objections.

Embodiments of the invention are illustrated in the accompanying drawings.

Referring to the drawings—Figure 1 shows in side elevation a press embodying the present improvements; Fig. 2 is a top plan view of the construction shown in Fig. 1, with parts thereof in section; Fig. 3 is an end elevation of the construction shown in Fig. 1; Fig. 4 is a side elevation, with parts in section, showing a modification of the construction illustrated in the foregoing views; and Fig. 5 shows a transverse section of a portion of the construction illustrated in Fig. 4.

Referring first to Figs. 1, 2 and 3 of said drawings, A indicates the frame of the machine, B the bed, C the reciprocating plunger, and D a plurality of tie-rods connecting the frame and bed, and constituting guides for the plunger. E¹, E², E³, E⁴ designate a plurality of crank shafts arranged transversely of the frame, instead of longitudinally as in present constructions. F designates a plurality of connecting rods connecting the cranks to the plunger. The

cranks E¹, E², E³, E⁴ are rotated from a drive shaft G through a suitable train of reducing gears and pinions g, g¹, g², g³, g⁴, g⁵, g⁶ and the gears g⁷, g⁸, g⁹, g¹⁰. An even number of crank shafts E¹, E², E³, E⁴ is 60 preferably provided, and they are so arranged that the diagonal thrust transmitted to the plunger from one crank shaft when off center will be counteracted by that of another. They are furthermore so arranged that the total effect of the diagonal thrusts of the crank shafts is to exert a compressing stress transversely of the plunger, rather than a tensional stress. As shown in the drawings, the two shafts E¹ and E² are 70 adapted to rotate both in the same direction and the shafts E³ and E⁴ are adapted to rotate both in the same direction and in the opposite direction to the shafts E¹ and E², thereby counteracting the diagonal thrust 75 transmitted to the plunger from the crank shafts E¹ and E² when off center. The rotation of the shafts, as described above, is effected by means of the pinions g⁵ and g⁶ meshing with the gears g⁷ and g⁸ and g⁹ and g¹⁰ of each pair of crank shafts. Any number of pairs of crank shafts may be provided. The connecting rods preferably have their ends f fitted in sockets f¹ in the lower side of the plunger and may be retained in the sockets by means of transverse pins f². (See Fig. 3.) The ends f of the plunger are also preferably provided with broad side faces f³ which closely engage the side-faces of the sockets and thereby serve 85 to counteract any transverse rocking of the plunger.

The press is preferably adapted to have sections added thereto at its ends, when it is desired to lengthen the press. For this purpose the ends of the plunger and bed may be dove-tailed as at I and have fitted thereto bed and plunger sections J and K of another section of press, and the rotation of the crank shafts is, preferably such that the 95 stresses between the sections of the plunger will be compressive rather than tensile, thereby relieving the connection of strain.

In Figs. 4 and 5 of the drawings is shown a construction wherein structural iron or 105 steel is used for the frame, and comprising a plurality of longitudinal I-beams or girders L, L united by transverse webs or plates M secured to the I-beams by bolts and flanges. This construction is of advantage 110

- inasmuch as the press may be manufactured and shipped in parts and assembled at its place of destination. A simplified form of transmission is shown in Figs. 4 and 5. The 6 pinions g^6 and g^6 driving the gears g^7 g^8 and g^9 g^{10} connected to the several crank shafts E^1 E^2 E^3 and E^4 , may be driven from a single drive shaft O through worms o^1 o^2 and worm gears o^3 o^4 .
- 10 The invention is not confined to the embodiment shown and described but modifications and changes may be made therein without departing from the spirit of the invention.
- 15 What is claimed is:—
1. In a power press for heavy work, the combination of a plunger, and a plurality of crank-shafts connected to said plunger, and means for rotating said shafts in opposite directions whereby the diagonal thrust transmitted to the plunger by one crank-shaft, when off center, will be counteracted by that of another, each of said crank shafts being continuously rotatable in one direction.
  2. In a power press for heavy work, the combination of a plunger, a plurality of crank-shafts, connections between said crank-shafts and said plunger, and means 20 for rotating said shafts in opposite directions whereby the diagonal thrust transmitted to the plunger by one crank-shaft, when off center, will be counteracted by that of another, each of said crank shafts being continuously rotatable in one direction.
  3. In a power press for heavy work, the combination of a plunger, a plurality of crank-shafts, crank connections pivotally connected to said plunger upon an axis per-
  - 40 pendicularly above that of said crank-shafts, and means for rotating said shafts in opposite directions whereby the diagonal thrust transmitted to the plunger by one crank-shaft, when off center, will be counteracted by that of another, each of said crank shafts being continuously rotatable in one direction.
  4. In a power press for heavy work, the combination of a plunger, a plurality of 50 crank-shafts connected to said plunger and means for rotating said shafts in opposite directions in pairs, whereby the diagonal thrust transmitted to the plunger by one crank-shaft, when off center, will be counteracted by that of another, each of said crank shafts being continuously rotatable in one direction.
  5. In a power press for heavy work, the combination of a plunger, a plurality of 55 crank-shafts connected to said plunger, gears on said crank-shafts, and pinions engaging gears on pairs of crank-shafts and rotating said gears on one pair in an opposite direction to those in another, where-
  - 60 by the diagonal thrust transmitted to the plunger by one crank-shaft, when off center, will be counteracted by another.
  6. In a power press for heavy work, the combination of a plunger and bed made in sections and the sections connected together, and a plurality of crank-shafts connected to said plunger, and means for rotating said shafts in opposite directions, whereby the diagonal thrust transmitted to the plunger by one crank-shaft, when off center, will be counteracted by another, each of said crank shafts being continuously rotatable in one direction.
  7. In a power press for heavy work, the combination of a plunger, and a plurality of 70 crank-shafts connected to said plunger, and means for rotating said shafts in opposite directions, whereby the diagonal thrust transmitted to the plunger by one crank-shaft, when off center, will be counteracted by another, said means comprising gears on said crank-shafts, pinions for driving said gears on said crank-shafts in pairs, worm-gears on said pinions, a drive-shaft, and worms on said drive-shaft adapted to 75 drive said worm gears in opposite directions.
  8. In a power press for heavy work, the combination of a plunger, and a plurality of 80 crank-shafts connected to said plunger, and means for rotating said shafts in opposite directions whereby the diagonal thrust transmitted to the plunger by one crank-shaft, when off center, will be counteracted by that of another, said means comprising gears on said crank-shafts, pinions for driving said gears on said crank-shafts in pairs, worm-gears on said pinions, a drive-shaft, and worms on said drive-shaft adapted to 85 drive said worm gears in opposite directions.
  9. In a power press for heavy work, the combination of a plunger, and a plurality of 90 crank-shafts, connecting rods, said rods and plunger having inter-engaging parts adapted to counteract transverse rocking of said plunger, and means for rotating said shafts in opposite directions whereby the diagonal thrust transmitted to the plunger by one crank-shaft, when off center, will be counteracted by that of another, each of said crank shafts being continuously rotatable in one direction.
  10. In a power press for heavy work, the combination of a plunger, and a plurality of 95 crank-shafts connected to said plunger, and means for rotating said shafts in opposite directions whereby the diagonal thrust transmitted to the plunger by one crank-shaft, when off center, will be counteracted by that of another and in directions to produce a compressive stress in the plunger between one shaft and another rotating in an opposite direction, each of said crank shafts being continuously rotatable in one direction.
  11. In a power press for heavy work, the combination of a plunger, and a plurality of 100 crank-shafts, connecting rods, said rods and plunger having inter-engaging parts adapted to counteract transverse rocking of said plunger, and means for rotating said shafts in opposite directions whereby the diagonal thrust transmitted to the plunger by one crank-shaft, when off center, will be counteracted by that of another, each of said crank shafts being continuously rotatable in one direction.
  12. In a power press for heavy work, the combination of a plunger, and a plurality of 105 crank-shafts, connecting rods, said rods and plunger having inter-engaging parts adapted to counteract transverse rocking of said plunger, and means for rotating said shafts in opposite directions whereby the diagonal thrust transmitted to the plunger by one crank-shaft, when off center, will be counteracted by that of another, each of said crank shafts being continuously rotatable in one direction.
  13. In a power press for heavy work, the combination of a plunger, and a plurality of 110 crank-shafts, connecting rods, said rods and plunger having inter-engaging parts adapted to counteract transverse rocking of said plunger, and means for rotating said shafts in opposite directions whereby the diagonal thrust transmitted to the plunger by one crank-shaft, when off center, will be counteracted by that of another, each of said crank shafts being continuously rotatable in one direction.
  14. In a power press for heavy work, the combination of a plunger, and a plurality of 115 crank-shafts, connecting rods, said rods and plunger having inter-engaging parts adapted to counteract transverse rocking of said plunger, and means for rotating said shafts in opposite directions whereby the diagonal thrust transmitted to the plunger by one crank-shaft, when off center, will be counteracted by that of another, each of said crank shafts being continuously rotatable in one direction.
  15. In a power press for heavy work, the combination of a plunger, and a plurality of 120 crank-shafts, connecting rods, said rods and plunger having inter-engaging parts adapted to counteract transverse rocking of said plunger, and means for rotating said shafts in opposite directions whereby the diagonal thrust transmitted to the plunger by one crank-shaft, when off center, will be counteracted by that of another, each of said crank shafts being continuously rotatable in one direction.
  16. In a power press for heavy work, the combination of a plunger, and a plurality of 125 crank-shafts, connecting rods, said rods and plunger having inter-engaging parts adapted to counteract transverse rocking of said plunger, and means for rotating said shafts in opposite directions whereby the diagonal thrust transmitted to the plunger by one crank-shaft, when off center, will be counteracted by that of another, each of said crank shafts being continuously rotatable in one direction.
  17. In a power press for heavy work, the combination of a plunger, and means for 130

reciprocating said plunger, said means comprising a plurality of drive rods greater than two each adapted to deliver a force having a horizontal component to said plunger, said rods being arranged so that the horizontal component of one rod will counteract that of another.

12. In a power press for heavy work, the combination of a plunger and a plurality of crank shafts greater than two connected to said plunger, and means for rotating said shafts in opposite directions

whereby the diagonal thrust transmitted to the plunger by one crank shaft, when off center, will be counteracted by that of another, each of said crank shafts being continuously rotatable in one direction. 15

In witness whereof, I have hereunto signed my name in the presence of two subscribing witnesses.
